FEELER MECHANISM FOR LOOMS

Filed Nov. 13, 1929

INVENTOR:
Alfred C. Stafford
BY Oscar J. Fain
ATTORNEY

UNITED STATES PATENT OFFICE

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE

FEELER MECHANISM FOR LOOMS

Application filed November 13, 1929. Serial No. 406,800.

This invention relates to side slipping feeler mechanisms in which the feeler arm is mounted for movement towards and from the front of the loom and also in a direction longitudinally of the shuttle. This second characteristic of the feeler or feeler arm is utilized to bring into action a train of mechanism to effect replenishment of filling.

It has been heretofore common to provide 10 the feeler or feeler arm with a toothed filling engaging tip usually formed of metal, a vulcanized fibre and the like. In weaving certain kinds of filling, however, such for instance as silk, artificial silk and rayon, the recurring contacts of the filling engaging teeth with the filling have produced injurious effects upon the delicate threads which frequently appear in the finished cloth by what is known as "shiners", and one of the important 15 objects of the present invention is to provide a feeler tip which will not only avoid injury to the delicate filling but will side slip readily when the filling has reached a predetermined degree of exhaustion.

20 The feeler tip in the present invention is composed of layers of fabric such as canvas for instance impregnated with a phenolic condensation product fused together by heat for a given period of time.

25 A feeler tip constituted as above stated presents a slippery end as contra-distinguished from adhesiveness, so that when the filling has reached a predetermined degree of exhaustion the slippery character of the feeler tip permits the feeler to move longitudinally along the bobbin or filling carrier under the frontward pressure thereof.

The invention and novel features thereof will be best made from the following description and accompanying drawings of one 30 good practical form thereof.

In the drawings:—

Fig. 1 is a plan view of a side slipping feeler containing the present invention;

Fig. 2 is an exploded view showing the assembling relation of the feeler tip with the rear end portion of the feeler arm;

Fig. 3 is a section on the line 3—3 of Fig. 1, and

Fig. 4 is a perspective view showing the

feeler tip secured in operative position on the end of the feeler arm.

The details of the mechanism whereby filling replenishment is effected upon side slipping movement of the feeler is not herein shown and described because such trains of mechanism are now well understood and the details thereof form no part of the present invention.

The feeler mechanism illustrated by Fig. 1 60 may be of the same general character as that shown and described in the patent to Larkin H. Brown and George E. Repass, No. 1,593,426, dated July 20, 1926, and the feeler arm of said patent as shown by Fig. 1 has the novel characteristic feeler tip of the present invention secured thereto.

The feeler stand 1 has mounted thereon for floating movement the feeler arm 2 the front end portion of which extends laterally as at 3 and the end portion of the laterally extending arm 3 is adapted to engage a step 4 mounted on the feeler stand. A rearwardly extending spring 5 is connected at 6 with the lateral arm 3 of the feeler and has its rear end portion secured to a stud 7 formed on the feeler stand, the construction being such that the spring 5 normally tends to move the feeler into its rearward filling position.

Extending laterally from the feeler stand is 80 the transmitter 8 the end of which extends into the feeler stand and rests against or in close proximity to the feeler arm 2, so that on side slipping movement of the feeler the transmitter 8 will be moved longitudinally 85 connecting through the usual train of mechanism to initiate replenishing of filling. The parts so far described may be of the same general character as the similar parts of the Brown and Repass patent.

The rear end portion of the feeler arm 2 is provided with a loop 9, which likewise may be generally like the similar loop of the Brown and Repass patent, but in the present instance the side members 10 and 11 of the loop are flattened as more clearly illustrated in Figs. 2 and 3, thus acting as a seat for the feeler tip as will presently appear.

As herein stated one of the purposes of the present invention has been to avoid injury

to the delicate filling such as silk, artificial silk, rayon and the like by the constant recurring contacts of the feeler tip therewith and at the same time to provide for ready side slipping movement of the feeler tip longitudinally of the filling carrier or bobbin when the filling is substantially exhausted.

The feeler tip in the present invention is formed of a fabric such as canvas impregnated with a phenolic condensation product while it is plastic and thereafter the impregnated fabric is subjected to pressure and heat treatment to harden the condensation product. A feeler tip formed generally as described possesses certain characteristics which prevent injury to the delicate filling on detecting beats and readily slides longitudinally along the filling carrier or bobbin surface when the filling has become substantially exhausted.

In accordance with the present invention the feeler tip is formed in two parts which are adapted to house between them and enclose the rear end or looped portion of the feeler arm. In effecting this purpose one part 12 of the feeler tip is provided with a flange 13 which extends from the body of the part 12 and is adapted to enclose the rear end portion of the feeler loop 9 against which the inner surface of the flange 13 rests.

The second part 14 of the feeler tip is formed generally of the same shape and contour as that of the first part but preferably has no flange although this may be otherwise varied. In the construction shown as one good practical form of the invention the two parts 12 and 14 of the feeler tip are secured to the feeler loop, one above and the other below and together with the flange 13 of the feeler tip serve to enclose and house the loop end portion of the feeler arm.

In view of the slippery character of the feeler tip formed as hereinbefore described of a fabric or canvas impregnated with a phenol condensation product, it is desirable that the flange portion 13 of the part 12 be provided with a series of filling engaging teeth 15 which are preferably arranged in the arc of a circle, while the other part 14 of the feeler tip is similarly provided with a series of teeth 16 which coordinate with the teeth 15 of the part 12 when the members of the feeler tip are in assembled relation as indicated in Fig. 4.

When the members of the feeler tip are to be secured in operative position to house the end of the feeler arm loop, one of the parts is placed above and the other below the loop 9 and fastening devices are passed through each of the parts of the feeler tip and the opening of the loop 9 as clearly indicated in Figs. 1 and 3.

In the present instance of the invention the securing means for the feeler tip consists of two clamping studs 17 and 18 of Fig.

3 which are passed through openings 19 and 20 of one part of the feeler tip and after passing through the loop 9 of the feeler arm extend through openings 21 and 22 of the oppositely disposed part of the feeler tip.

As represented in Fig. 2 the studs 17 and 18 which are provided with a head 23 rest in sockets 24 of one part of the feeler tip to thereby prevent catching of filling or lint during weaving. The opposite end portion 70 of the studs 17, 18 is upset as indicated at 25 Fig. 3, the construction being such that the two parts of the feeler tip are secured in operative position on the flattened loop portion of the feeler arm with the inner surface 80 of the flange 13 resting against the end portion of the feeler arm loop and one of the studs 18 as shown rests against the inner surface of the rear portion of the feeler arm loop, the result being that the two members 85 of the feeler house and enclose the feeler arm loop and are prevented from slipping movement by one of the studs as 18 on the one hand and the rear portion of the loop on the other.

The invention is not necessarily limited to the particular means for securing the two parts of the feeler tip to the feeler arm as different forms of securing means may be readily suggested by one skilled in the art.

What is claimed is:—

1. In a feeler mechanism for looms, the combination of a feeler stand, a feeler arm mounted upon the feeler stand for side slipping movement; a filling engaging tip formed of a fabric impregnated with a phenolic condensation product hardened by heat treatment and secured to the end of the feeler arm, and a series of teeth cut transversely of the filling engaging tip and possessing a slippery filling engaging surface.

2. In a feeler mechanism for looms, the combination of a feeler stand, a feeler arm mounted upon the feeler stand for side slipping movement, and a two part filling engaging tip formed of a fabric impregnated with a phenol condensation having a series of filling engaging teeth that the slippery character of the teeth may enable the feeler to readily side slip when the filling is substantially exhausted.

3. A feeler arm mounted for side slipping movement by the forward pressure thereon and having a two part filling engaging tip formed of canvas impregnated with a phenol condensation product, one of said parts having a flange for housing the rear end of the feeler arm and provided with a series of filling engaging teeth, and means for securing the two part tip upon the end of the feeler arm.

4. A feeler arm mounted for side slipping movement by the forward pressure thereon, and having a looped rear end portion, a two part filling engaging tip each formed of fabric impregnated with a phenol condensa-

tion product, one of said parts having a flange, the inner surface of which rests against the rear of the feeler arm loop and the outer surface of which flange is provided with teeth, and means for securing the two parts of the tip together, one above and one below the feeler arm loop.

5 5. A feeler arm mounted for side slipping movement and having a looped rear end portion, a two part filling engaging tip formed of canvas impregnated with a phenol condensation product, one of said parts having a curved flange in rear of the feeler arm loop, and means for securing the two parts of the
10 bakelized canvas tip together in housing relation with the feeler arm loop.

15 In testimony whereof, I have signed my name to this specification.

ALFRED E. STAFFORD.
